Application July 5, 1947, Serial No. 759,184
1 Claim. (Cl. 131—212)

ANTINICOTINE CIGARETTE HOLDER

Otto G. Brawner, Fort Worth, Tex., assignor of
two-thirds to J. L. Breathwit, Dallas, Tex.

Application July 5, 1947, Serial No. 759,184

1 Claim. (Cl. 131—212)

1. This invention relates to smokers' articles and

more particularly to cigarette and cigar holders designed and constructed to intercept products of condensation such as tobacco tars in their passage from the burning tobacco to the smoker's mouth.

The principal object of the invention is to provide a cigar or cigarette holder or pipe stem whose peculiar construction obviates the necessity for a filter employed in some cases to absorb or modify the effect of nicotine and harmful tars present in smoking tobacco. The invention aims instead to provide a sectional holder in which the sections each are provided with a longitudinal passage and interconnecting parts, the passage in at least one of the sections being closed except for lateral smoke inlets and outlets or parts, to define a chamber for entrapment of products of condensation harmful to the smoker. Other of the sections, by virtue of their manner of joining, one with the other, produce additional traps for the same purpose and constrain the smoke to pass in a circuitous course from the burning tobacco to the smoker's mouth comparatively free of injurious components.

Another object of the invention is to provide a cigarette or cigar holder or pipe stem whose sectional parts are easily assembled and as easily disassembled for cleaning, thus affording a holder which can be kept in a sanitary condition and comparatively free of the strong and obnoxious tobacco odors usually attending devices of this nature.

With the foregoing objects in view, the invention has further reference to certain features of accomplishment which will become apparent as the description proceeds, taken in connection with the accompanying drawing wherein:

Figure 1 is a view of the invention assembled. Figure 2 is a view showing all of the parts of the holder separated.

Figure 3 is a view in longitudinal section.

Figure 4 is a view in transverse section, taken on line 4—4 on Figure 3.

Figure 5 is another view in transverse section, taken on line 5—5 on Figure 3, and

Figure 6 is a fragmentary view, partly in longitudinal section, showing the course of smoke through the principal sections of the holder.

Continuing with a more detailed description of the drawing, it is to be observed that for purposes of explanation, the invention is shown as embodied in a cigar or cigarette holder, it being obvious that the same general arrangement can be embodied in a pipe stem. Accordingly, 55 will collect in the closed passages or traps such

reference numeral 10 denotes a tubular section adapted to receive a cigar or cigarette and whose walls are straight. One end of this tube is telescopically received in the end of a similar but larger tube 11. Enclosed within the two tubes 10 and 11 is a core 12 having a reduced portion 13 which is received by and frictionally held in the inner end of the first tube 10. The end 14 of the core 12 next adjacent to the portion 13 thereof is further reduced in diameter to define an annular space 15 between the same and the inner walls of the tube 10 for the purpose to be presently explained.

The core 12 has an annular shoulder 16 abutting against the inner end of tube 10 and its opposite end 17 is tapered, as shown and provided with longitudinal, circumferentially spaced grooves 18 whose purpose will be explained later.

The tapered end 17 of the core 12 provides an annular space 19 between the same and the inner walls of the tube 11 into which is inserted one end of a sleeve 20 whose walls are preferably expanded at the midsection of the sleeve but not necessarily so. The end of tube 11 frictionally engages the exterior surface of sleeve 20 while the inner end of the latter frictionally engages the tapered end of the core 12. The reduced end 21 of a bit 22 is frictionally retained in the opposite end of the sleeve 20.

The core 12 has a longitudinal passage 23 therethrough but its ends are closed by plugs 24, the only openings to the passage 23 being ports 25 at one end and ports 26 at the opposite end, positioned at right angles to ports 25. Thus, the passage 23 becomes a trap for products of condensation, as will become apparent presently.

From the foregoing, it is apparent that smoke from a cigar or cigarette mounted in the end of tube 10 will, upon suction through the bit 22, pass into the annular space 15 between the extremity of the core 12 and tube 10 and will enter the trap 23 of the core 12 through ports 25. The smoke will emerge from the trap 23 through ports 26, entering the annular space 19 about the tapered end of the core. From this space, which is also a trap for tar deposits, the smoke will enter the sleeve 20 through the grooves 18 of the core and will pass into the smoker's mouth through the bit 22 comparatively free of injurious substances contained originally in the smoke and which, for the most part, have been deposited on the walls of the various passages through which the smoke is constrained to flow. Condensation

as at 23 and 19, to be cleaned out periodically by separating the sections of the holder.

Manifestly, the construction as shown and described is capable of some modification and such modification as may be construed to fall within the scope and meaning of the appended claim is also considered to be within the spirit and intent of the invention.

What is claimed is:

A cigarette holder including a plurality of sections held frictionally in end to end relationship, the smallest one of said sections comprising a tube defining a cigarette socket, another of said sections comprising a tube receiving said smallest tube, a hollow core having smoke inlet ports in communication with said smallest tube, one end thereof being frictionally held in the end of said smallest tube and concealed by the latter and the next adjacent tube, said core further having a tapered, longitudinally grooved end, a sleeve having one end frictionally engaging the tapered end of said core and the adjacent end of said next

adjacent tube and enclosing the said tapered portion of said core to define a condensation trap and to constrain smoke entering said core to pass through the grooves of the latter into said sleeve, and a bit retained in the opposite end of said sleeve.

OTTO G. BRAWNER.
